TRAIN ORDER RING

Original Filed Feb. 13, 1930

UNITED STATES PATENT OFFICE

CLARENCE CLIFFORD RAUSCH, OF EVANSVILLE, INDIANA

TRAIN ORDER RING

Original application filed February 13, 1930, Serial No. 428,218, now Patent No. 1,795,679, dated March 10, 1931. Divided and this application filed January 7, 1931. Serial No. 507,242.

This application is a division of my application Serial No. 428,218, filed February 13, 1930, which is now Patent No. 1,795,679, dated March 10, 1931.

5 The common practice involved in delivering an order from a railroad or signal station to the engineer or fireman of a passing train, is for the engineer to slow down sufficiently to enable an order carrying ring to be caught from the station agent or operator's hand by the engineer or fireman as the train passes.

The object of the present invention is to provide an improved train order holding 15 ring, adapted to be held at the signal station or railroad station and to receive a catcher on the train. My improved train order holding ring has a compartment to contain the order or message, and a closure which is pivoted to the ring, covers the opening leading to the aforesaid compartment, and is arranged so that when being caught by the catcher on the train, the closure will be prevented from opening, thus insuring security 20 of the order or message in the compartment.

To enable a clear understanding of the nature, construction, and operation of the ring to be had, disclosure is hereinafter given of a holder for the ring and a catcher on the train.

25 In the accompanying drawings:

Figure 1 is a front elevation, parts being broken away, showing the deliverer in operation;

Fig. 2 is a plan view of the apparatus on 35 the train and at the station, illustrating how the ring is caught when the catcher is extended;

Fig. 3 is a front view of the catcher, in 40 folded position;

Fig. 4 is a detail view of the order holding ring; and

Fig. 5 is an end view of the ring holder, parts being in section.

45 I have illustrated my present invention in connection with an improved catcher, which is set forth and claimed in my Patent No. 1,795,679.

In Fig. 1, a part of a locomotive is shown 50 at 1 and a part of a railroad station, signal

tower, or other suitable structure, appears at 2.

One part of the apparatus is carried by the locomotive 1 and the other part by the structure 2. The train order holding rings 55 appear at 3.

The apparatus on the train embodies a suitable attaching plate 4 fastened in any desired manner by screws or bolts passing through holes 5 and to this plate, there is hinged on 60 a vertical pintle 6, an arm 7 which is adapted to swing. The arm 7 is provided with a handle 8 which may be grasped by the fireman, engineer or trainman to draw the arm back into folded position, as shown by dotted lines 65 at the upper part of Fig. 2 or to extend said arm into operative position, as shown by full lines at the upper part of Fig. 2. The pintle 6 is adapted to turn in bearings 9 and it also is slidable vertically in said bearings, there 70 being provided cushion springs 10 surrounding said pintle which enable the arm to move up and down in a cushioned manner so that, regardless of the rocking of the train or because the catcher does not properly line up 75 with the lowermost ring 3, the arm will adjust itself so that it will catch the ring without unnecessary shock or damage resulting in the parts of the apparatus.

The arm 7 carries a catcher 11, made of 80 spring steel, whose feet have a slot and pin connection 12 with the arm so that the catcher may compress and expand, enabling it to enter ring 3, compressing as it does so and then to expand to hold the ring in the constricted or reduced parts 13, as best seen in Fig. 2. This construction prevents the ring from falling off of the catcher.

Spring clips 14, 15, carried by the plate 4, hold the arm 7 in its folded and extended 90 positions. The clip 15 is adapted to co-operate with the rod 16 on the arm 7. The clip 14 embraces the arm.

On the station or structure, there is provided an inclined chute 17 which may be 95 guyed in any suitable manner as at 18. The chute has resilient arms 19 extending beyond its lower end and carries transverse arc-shaped clips 20, the ends of the arms being slightly turned inwardly at 21, the clips and 100

arms holding the rings, as shown in Fig. 1.

The ring is provided with a compartment 22, shown in dotted lines in Fig. 4 for containing the train order. Hinged to the ring 5 at 23 is an inwardly turning closure or door 24 of arc-shape which, due to its form, cannot accidentally open when the catcher 11 strikes the ring, because the tendency of the catcher is to wedge into the ring and such 10 action keeps the door or closure 24 closed. The closure is not only arc shaped in length but also in cross sectional shape so that it forms a part of the ring and conforms to the shape thereof.

15 The operator at the signal station merely deposits the rings containing the orders in the chute 17 for the train for which they are intended.

When the station is approached, the engineer or fireman grasps the handle 8 and swings arm 7 outwardly at right angles to the base 4, as shown in full lines in Fig. 2, whereupon the catcher 11 is in line with the lowermost or outermost ring 3 which is then 20 caught and passes to the constricted part 13. As soon as the ring is caught, the next ring falls into place so that the conductor or brakeman may also swing a duplicate apparatus located at some convenient point on the train 25 and catch the ring independently of the engineer or fireman. When the order ring has been caught, the arm 7 is retracted to the dotted line position in the upper part of Fig. 2. The dotted line showing at the lower 30 part of Fig. 2, illustrates the advance of the catcher as the train proceeds after the ring has been caught.

What I claim is:

40 A train order holding ring having a compartment, and an arc-shaped closure for said compartment, said closure being pivoted to the ring and adapted to open inwardly toward the center of the ring.

In testimony whereof I affix my signature.

45 CLARENCE CLIFFORD RAUSCH.
